TOY CONSOLE FOR CHILD'S VEHICLE

Lawrence T. Jones, Olney, Ill., assignor to American Machine and Foundry Company, a corporation of New Jersey

Filed Dec. 16, 1965, Ser. No. 214

Term of patent 14 years

(Cl. D34—15)

FIG. 1 is a front perspective view of a toy console for a child's vehicle, showing the front, top and one side of my new design; and

FIG. 2 is a rear perspective view showing the back, bottom and other side thereof.

I claim:

The ornamental design for a toy console for child's vehicle, substantially as shown.
